UNITED STATES PATENT OFFICE.

THOMAS GEORGE BAXENDEN, OF WATFORD, ENGLAND.

SPOOL FOR PHOTOGRAPHIC-CAMERA FILMS AND SIMILAR PURPOSES.

Application filed March 26, 1925. Serial No. 18,612.

To all whom it may concern:

Be it known that I, THOMAS GEORGE BAXENDEN, a subject of the King of Great Britain, of "Lawrenny," Hempstead Road, Watford, in the county of Hertford, England, have invented a new and useful Improvement in or Relating to Spools for Photographic-Camera Films and Similar Purposes, of which the following is a specification.

This invention relates to metal spools for photographic camera films and similar purposes.

I have described in my previous application for U. S. A. patent, Serial No. 740,288, a metal spool consisting of a body part rolled up from a sheet metal blank and having the discs which form the end flanges attached to the body part by electric welding.

The present invention has for its object to provide an improved construction particularly adapted to facilitate the electric welding of the end discs to the body of the spool.

To this end, and according to the present invention, the ends of the tubular body part are turned outwardly or inwardly to a small extent so as to provide at each end a narrow flange, the face of which abuts against the inner face of the end disc and provides a double thickness of metal at this point whereby the electric welding operation can be carried out in a practical and more efficient manner and a neat integral connection obtained.

The improved metal spool is provided with the usual slots for receiving the end of the photographic film and the end discs are provided with the usual pin hole at one end and slot for the winding key at the other.

The accompanying drawings illustrate a metallic spool embodying the present invention and some modified forms thereof.

Fig. 1 is an elevation partly in section showing the separate parts of the improved spool before assembling.

Fig. 2 is an elevation of the finished spool partly in section,

Fig. 3 is a partial view in section, and

Fig. 4 is an end view of a modified construction.

Figs. 5 and 6 are partial views in section of two other modified constructions.

In Figs. 1 and 2, *a* is the tubular body of

the spool which is conveniently rolled up from a metal blank, one edge of which is cut away so that when rolled up the end portions *b* overlap the opposite edge whilst at 60 the intervening portion the edges remain spaced apart to provide a slot *c* for the reception of the end of the film which is to be wound on the spool in the usual manner. Each end of the tubular body part *a* thus 65 formed is turned or flared outwardly for a short distance to provide a narrow flange *d*. Alternatively the flanges *d* may be turned inwardly as in Fig. 6.

e and *f* are the end discs, one of which is 70 provided with a central hole, and the other with a slot for the winding key.

In manufacturing the finished spool the narrow flanges *d* are placed so as to abut against the inner faces of the corresponding 75 end discs *e* and *f* and are electrically welded to the said discs at the junction of the flanges *d* therewith, thus producing a spool in which the end discs and body part are made integral by welding, the welding operation being greatly facilitated by the double 80 thickness of metal provided at the point of connection by the narrow flanges *d*.

If desired the overlapping end parts *b* of the tubular body *a* may also be welded together.

The finished integrally constructed spool made in accordance with the present invention is strong and of good appearance.

As shown in Figs. 3 and 4, the end discs 90 *e* and *f* forming the flanges of the spool may be embossed or otherwise provided with outer rolled edges *h* and raised centre bosses *i* where such are required by any particular make of camera.

Further, and as shown in Fig. 5, in adapting the improved spools for use with cameras where long winding keys are employed a suitably perforated stop piece such as *g* is fitted across the interior of the hollow body part *a* by making said stop piece of U shaped form and connecting the ends of the said U shaped stop to the inner face of the adjacent end disc *f* by electric welding.

What I claim as my invention and desire 105 to secure by Letters Patent is:—

1. A metal spool such as used for photographic films comprising the combination of two end discs, a tubular body part having its ends formed with narrow flanges which abut against the end discs and are welded thereto, an inner perforated stop 110

piece welded to one of the discs and arranged to be engaged by a long winding key where such are employed.

2. A metal spool such as used for photographic films comprising the combination of a tubular body part rolled up from a flat metal blank, the end parts of which overlap whilst the intermediate edges are spaced apart to provide a slit for receiving the film, narrow flanges being formed upon the

ends of said tubular body part, and end discs abutting against the narrow flanges on the body part and made integral with the latter by electric welding the overlapping portions of the body part being also electrically welded, a U-shaped perforated stop piece electrically welded to the interior of that end disc which receives the winding key, said stop lying within the tubular body part. 15

THOMAS GEORGE BAXENDEN.
